Bernard C. Howell and Francis F. Melvin, Elwood,
Ind., assignors to Loose-Wiles Biscuit Company,
Long Island City, N. Y., a corporation of New
York

Application March 20, 1940, Serial No. 91,106

Term of patent 7 years

To all whom it may concern:

Be it known that Bernard C. Howell and Francis F. Melvin, both citizens of the United States, residing at Elwood, in the county of Madison and State of Indiana, have invented a new, original, and ornamental Design for a Display Rack, of which the following is a specification, reference being had to the accompanying drawings, forming a part thereof.

In the drawings:

Fig. 1 is a front perspective view of a display rack, showing our new design;

Fig. 2 is a side elevational view;

Fig. 3 is a front elevational view; and

Fig. 4 is a rear elevational view.

We claim:

The ornamental design for a display rack, substantially as shown.

BERNARD C. HOWELL.
FRANCIS F. MELVIN.
